TARPAULIN

Filed June 4, 1947

so that they will apply the load to the cord, and hence some variation in manner of mounting them is permissible within the limits of this principle.

It is found that a tarpaulin constructed as herein indicated is very much stronger than any heretofore in use. This comes about particularly because of the cording and the disposition of the grommets adjacent the cording, and also within the multiple thickness of the hem material.

What is claimed is:

1. In a tarpaulin, a sheet of fabric material, a side hem thereon consisting of an overlapped edge of the sheet stitched down in overlapped relation, an end hem of like construction, said hems overlapping in a corner, the said hems providing a continuous recess for reception of a cord, a flexible cord in said recess of both hems, the cord extending around the corner, being continuous on said side and said end, and a grommet including a center tubular section passing through the overlapping hems at the corner, said grommet being disposed adjacent the cord so as to transmit substantially directly to the cord outward forces applied to the grommet.

15

2. In a tarpaulin or the like, a sheet of material having a plurality of edges with at least one corner between adjacent edges, and with the edges thereof folded over so as to form a hem around the material, said hems overlapping at the corner, a continuous flexible cord enclosed in the hem adjacent the outer edge thereof and extending around the corner, and a grommet in said corner of the hem portion of the sheet adjacent said cord, said grommet being fastened to the material and to the cord.
